COMBINATION POCKET KIT

Morris Schein, Brooklyn, N. Y.

Application July 22, 1936, Serial No. 91,852

2 Claims. (Cl. 150—34)

This invention relates to new and useful improvements in a combination pocket kit.

The invention has for an object the construction of a combination pocket kit which is characterized by a main central pocket, smaller pockets arranged on one of the sides thereof and other pockets arranged on the other side thereof.

Still further the invention proposes to so construct the pocket kit that it may be made from various sheet materials such as leather, canvas, cloths, etc.

Still further the invention contemplates constructing the combination pocket kit so that it is characterized by several superimposed strips 15 of material bent at a transverse line forming superimposed layers and securing the edges of these layers together with stitches so as to form pockets.

Another one of the objects of this invention resides in the provision of auxiliary strips of material secured on one of the walls of said pockets for forming additional pockets.

Still further the invention proposes an arrangement whereby certain of said strips are releasably held in position so that they may be removed and thus remove excessive pockets from the kit when desired.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a combination pocket kit constructed according to this invention.

Fig. 2 is a rear perspective view of Fig. 1.

Fig. 3 is a transverse sectional view taken on the line 3—3 of Fig. 1.

Fig. 4 is a perspective view of a kit similar to the one illustrated in Fig. 1 but of modified form.

Fig. 5 is a horizontal sectional view taken on the line 5—5 of Fig. 4.

The combination pocket kit, according to this invention, comprises several superimposed strips of material 10, 11 and 12 bent at a transverse line 13 forming several superimposed layers 10^a and 10^b, 11^a and 11^b, and 12^a and 12^b. These layers are secured together by lines of stitches 14 along the sides of the combination pocket kit and thus produce pockets. The layers 10^a and 10^b produce a large main central pocket 10'.

The layers 10^b and 11^b form a pocket 15. The layers 11^b and 12^b form a pocket 16; the layers 10^a and 11^a form a pocket 17; and the layers 11^a and 12^a form a pocket 18. The upper edge of the layer 11^a is slightly higher than the upper edge of the layer 12^a so that it is exposed and may easily be gripped by one's fingers and render the pockets adjacent it more convenient to open.

Several auxiliary strips of material are engaged within the pocket 15 and are associated with stitches forming additional pockets. There is a central strip of material 19 upon which a narrower and shorter piece of material 20 is engaged. The materials 19 and 20 are secured together by lines of stitches 21 along the edges of the material 20. This forms a pocket 22 between the material 19 and 20. Additional strips of material 23 and 24 are disposed within the pocket 15 and are secured by their outer edges in stationary positions by the said stitches 14. At 20 their inner edges the strips 23 and 24 are secured down by the stitches 21. Thus, additional pockets are formed. Lines of stitches 26 along the edges of the material 19 secure this material to the rear 10^b. This forms another pocket. 25 The layer 12^b is fashioned in the form of a wine glass (see Fig. 1) and auxiliary stitches 14' are engaged along the edges thereof. Thus, the pocket 16 is of wine glass shape formation.

In Figs. 4 and 5 a modified form of invention 30 has been disclosed in which stitches 21' serve to secure together the strips of material 19 and 20. In this form of the invention the strip of material 19 is not attached to the adjacent layer of material 10^b. The strips of material 23' and 35 24' are made of separate sections fixedly attached to the strip 20 by means of the stitches 21' and hook fasteners 27 serve to detachably connect the portion 19, 20, 23' and 24' to the adjacent section 10^b. These lines of hooked fasteners are controlled by a slide 28. The edges of the strips of the material 23' and 24' below the top edge of the layer 11^b, indicated by the reference numerals 23^a and 23^b respectively, are free and merely disposed within the pocket 15. 40 When it is desired the slides 28 may be moved upwards to disengage the hook fasteners 27 and then the strips 23' and 24' together with the strips 19 and 20 may be removed. The stitches 14 serve to hold one of the sections of the hook 45 fastener 27 upon the layer 10^b.

The operation of the device is as follows:—

A pencil may be placed within the compartment immediately below the strip 20. A comb may be placed within the compartment immedi- 55

ately behind the strip 19. Scissors and other small implements may be placed in the pockets immediately behind the strips 21 and 24. The other pockets may be used to hold papers, coins, 5 paper money, and the like.

While I have illustrated and described the preferred embodiments of my invention, it is to be understood that I do not limit myself to the precise constructions herein disclosed and the right 10 is reserved to all changes and modifications coming within the scope of the invention as defined in the appended claims.

Having thus described my invention, what I 15 claim as new, and desire to secure by United States Letters Patent is:—

1. A combination pocket kit comprising several superimposed strips of material bent at a transverse line forming several layers, lines of 20 stitches securing the edges of said layers together forming pockets, and auxiliary strips of material secured on one of the walls of one of

said pockets forming additional pockets, said auxiliary strips of material being removably secured within said pocket, with hook fasteners along the sides thereof.

2. A combination pocket kit comprising several superimposed strips of material bent at a transverse line forming several layers, lines of 10 stitches securing the edges of said layers together forming pockets, and auxiliary strips of material secured on one of the walls of one of 15 said pockets forming additional pockets, said auxiliary strips of material being removably secured within said pocket, with hook fasteners along the sides thereof, said hook fasteners extending between the top of said auxiliary strip of material down to an intermediate point of said auxiliary strips near the top of an adjacent strip so as to be readily accessible and the portion of said auxiliary strips extending into said strips being free therefrom. 20

MORRIS SCHEIN.
